(57) **CLAIM**

The ornamental design for a faucet, as shown and described.

DESCRIPTION

FIG. 1 is a perspective view of a faucet of the new design; FIG. 2 is a side view of the faucet of FIG. 1, wherein the view is the same from either side;

FIG. 3 is a front view of the faucet of FIG. 1;

FIG. 4 is a back view of the faucet of FIG. 1;

FIG. 5 is a top view of the faucet of FIG. 1; and,

FIG. 6 is a bottom view of the faucet of FIG. 1.

The portions of the Figures shown in phantom lines are not part of the claimed design but are for illustration only.
